APPARATUS FOR REJUVENATING BALL-POINT PENS

Henry W. Walden, New York, N. Y.

Application August 19, 1955, Serial No. 529,553

8 Claims. (Cl. 233—26)

This invention relates to an apparatus for rejuvenating ball-point pens and more particularly to a means by which apparently-empty ink-containing cartridges employed in such pens can be given a further period of useful writing life.

At the present time, most ball-point pens contain a removable and replaceable ink-containing cartridge, which usually consists of a relatively slender tube composed of either plastic material or metal and provided at one end with a metallic tip in which the ball-point is rotatively mounted. The ink contained in these cartridges is of a viscous nature and this, coupled with the small internal diameter of the body of the cartridge, often causes a substantial portion of the ink to adhere to the walls of the tube and never reach the ball-point. Also, at times air will enter the tube or cartridge, and will be trapped therein in a manner to prevent flow of the ink toward the point with the result that the pen will not write and the user mistakenly believes that the ink supply in the cartridge is depleted. As a result, he will purchase a new cartridge, despite the fact that the supposed empty one contains a substantial amount of ink or is often very nearly full and able to provide many lines of writing if the ink contained in it was caused to reach the ball-point. Very often also, the user of a pen of this kind for a substantial period will discard a half-empty cartridge when the pen ceases to write, believing that the ink supply is exhausted whereas the amount of ink adherent to the inner wall surfaces of the cartridge would be sufficient to greatly increase the period of writing usefulness of the cartridge.

It is therefore an object of the present invention to provide a relatively simple apparatus by means of which ball-point pens, containing an apparently-empty cartridge, can be given a further useful period of writing. It is an object of the invention to provide an apparatus of this kind which will tend to dislodge adherent or sluggish ink within the barrel or tube of the cartridge of the pen in a manner to cause said ink to be directed toward and against the ball-point so that the same will utilize such ink for smooth and easy writing.

It is an object of the invention to provide an apparatus as above mentioned which will enable the ink in a cartridge to be loosened and forced toward the point without requiring the cartridge to be removed from the pen during the rejuvenation treatment.

It is an object of the invention to provide means by which a cartridge-containing pen will be centrifuged by a simple and effective mechanism to cause the ink in the cartridge to be forced toward the point. It is an object of the invention to provide means which can be coin-controlled if desired, for subjecting the pen to the action of centrifugal force for a given period of time, to thereby treat the pen in a manner to force its ink toward the point and renew its writing ability.

It is an object of the invention to provide a relatively simple and inexpensive device which can be employed in banks, stores, business offices or other places where substantial numbers of ball-point pens are in constant use and where many half-empty ink cartridges are daily discarded in the erroneous belief that they are depleted of ink.

2

With these, and other objects to be hereinafter set forth in view, I have devised the arrangement of parts to be described and more particularly pointed out in the claims appended hereto.

5 In the accompanying drawing, wherein an illustrative embodiment of the invention is disclosed,

Fig. 1 is a vertical sectional view of an apparatus constructed according to the invention;

Fig. 2 is a sectional view, taken substantially on the line 2—2 of Fig. 1, looking in the direction of the arrows;

Fig. 3 is a front elevational view, on a smaller scale, of the apparatus;

Fig. 4 is a side elevational view on a small scale of the apparatus, and

15 Fig. 5 is a sectional view, taken substantially on the line 5—5 of Fig. 2, looking in the direction of the arrows.

Referring to the drawing, 1 indicates generally the casing or housing of the machine. The same may be 20 constructed of metal, plastic or of any other suitable material, and it includes a bottom wall 26 provided with suitable supporting feet 27 upon which the machine can be rested on a suitable supporting surface such as a table or desk top. Secured by the screws or rivets 25 upon the

25 bottom 26, is a bracket 3 upon which is mounted an electric motor 2. The shaft 5 of the motor 2 is secured by a set screw in a boss 6 provided centrally on a tube or cylinder 8 within which the pen 11 is inserted for treatment in a manner to be described. The tube or

30 cylinder 8 constituting the pen holder is open at one end, as indicated at 10, and is closed at its opposite end by a threaded, removable plug 9.

Diametrically opposite to the boss 6 on the tube 8, is another boss 13 in which a spindle 12 is secured by a set screw, said spindle being rotatively mounted in the side wall of the housing 1. Secured on the spindle 11 and located exteriorly of the casing 1, is a knob 14 provided with a pointer 20. The pointer is employed to indicate the point of loading of the pen into the tube 8 and the point of ejection for the pen.

Provided on the tube or cylinder 8 is an annular rim 18 which does not close the open top of the tube 8, nor does it extend over the removable plug 9 at the closed end of the tube. The rim 18 is rigidly secured to, and rotates with, the tube 8 and it is rotative within a circular chamber formed by the arcuate top 28 of the casing 1 and a curved strip 21 secured within the lower part of the casing 1.

The apparatus is designed to be operated by the closing 50 of a switch, which can, if desired, be a time-switch that is coin-controlled, so that upon deposit of the pen into the tube 8 through the entrance opening 17 in the housing, and the deposit of a coin through a coin slot 22, the motor 2 will be set in operation to rapidly rotate the tube 8 for a predetermined time.

A coin-controlled switch is indicated at 7, and since such switches are widely known, the details of the same are not shown herein. It is sufficient to state that each time a coin is deposited in the slot 22, the motor 2 will 60 be set in operation and will spin or rotate the tube 8 for a predetermined period. Wiring 19 extends from the switch to the motor 2. As an alternative for a coin-controlled switch, a conventional manually-operated switch mounted within or on the casing 1 and operated 65 externally of the casing may be employed.

From the foregoing, the operation of the pen-rejuvenating machine will be readily understood. A pen to be rejuvenated is dropped through the entrance opening 17 in the top of the casing 1. It will be noted that the pen cannot enter the tube 8 unless the open end 10 of the tube is in registry with the inlet opening 17. The operator can assure himself of such registration by manually turn-

ing the knob 14 until the pointer 20 thereof is located at the arrow 23 on the side wall of the casing. Any attempt to deposit the pen in the tube while the open end of the same is disaligned from the entrance opening 17 will be blocked by the rim 18, a part of which will be then disposed below the opening 17 except when the open end 10 or the plug-closed end 9 of the tube 8 is aligned with the opening 17.

The pen is inserted in the tube 8 with the pointed end of the pen disposed downwardly or resting against the closure plug 9 substantially as shown in Fig. 1. Switch 7 is then closed either by the deposit of a coin through slot 22, or by manual operation, and the motor 2 will thereupon rotate and will rapidly spin the tube or cylinder 8, thus imparting a rapid whirling action on the pen to cause any fluid within the cartridge of the pen, such as softened ink, or softened ink mixed with a solvent, a drop of which might be inserted in the cartridge in cases where the ink has hardened, to be urged by centrifugal force toward the pointed end of the pen. The pointed end of the pen, being forced hard against the inner face of the plug 9 will have its ball displaced slightly from its seat and this action will tend to cause the ink to be forced against and around the ball to aid in providing an initial starting action in writing when the pen is removed from the machine and is used for writing.

After the pen has been whirled for a relatively short time in the manner described, the motor will cease operation, either by manually opening the switch 7 or by the automatic timing mechanism therefor, and the pen is then ready for removal and writing. This is done by lining up the open end 10 of the tube 8 with an inclined outlet chute 16 provided in the front wall 15 of the facing 1. To secure this alignment, the knob 14 is manually turned until its pointer 20 is located at the arrow 24, or is positioned in the direction shown in Fig. 4. The pen will then slide out by gravity through the chute 16, with its rear end disposed forwardly so that it cannot soil the fingers. The interior of the tube or cylinder 8 may be cleaned whenever desired by removal of the plug 9 and a brush or rag pushed through the tube.

Tests have conclusively shown that by the use of the described apparatus, pen cartridges which have been discarded as being depleted of ink have had their useful writing life materially increased by the projection of adherent ink toward and against the ball-point by centrifugal action when the pen is rotated in the manner herein described.

Having described a single embodiment of the invention, it is obvious that the same is not to be restricted thereto, but is broad enough to cover all structures coming within the scope of the annexed claims.

What I claim is:

1. An apparatus for treating ball-point pens comprising, a tube open at one end and closed at its opposite end, a shaft attached to the tube at right angles to the longitudinal axis of the tube, a motor connected to the shaft for rotating the tube, a casing in which the tube is rotated, the casing having an opening through which a pen is passed to insert the pen into the tube, and guard means carried by the tube for blocking said opening when the open end of the tube is disaligned therewith.

2. An apparatus for treating ball-point pens comprising a casing having a circular chamber, a tube for holding a pen, said tube being open at one end and closed at its other end, a motor shaft attached to the tube at right angles to the longitudinal axis of the tube, the casing having a pair of openings, one of the openings being an inlet opening through which a pen is inserted to reach the tube when the tube has its open end aligned with the opening, the second opening being an outlet opening through which the pen is ejected after having been centrifuged by the rotative movement of the tube, and guard means rotatively carried by the tube for blocking

off both of the openings except when the open end of the tube is in alignment with one or the other of the openings.

3. In an apparatus as provided for in claim 2, where-
5 in a finger-piece is provided on the tube and is located externally of the casing, said finger-piece consisting of a knob and pointer, and indicating markings on the wall of the casing adjacent to the knob and pointer for indicating the positions to which the pointer is to be moved in
10 order to have the tube respectively receive and eject the pen.

4. An apparatus for treating ball-point pens comprising a tube open at one end and closed at the other, a shaft attached to the tube at right angles to the longitudi-
15 nal axis of the tube, a motor connected to the shaft for rotating the tube, a casing in which the tube is rotated, the casing having an opening at the top through which a pen is passed to insert the same into the tube, guard means carried by the tube for blocking said opening when the open end of the tube is disaligned therewith, and a coin-controlled time switch for causing operation
20 of the motor for a predetermined period.

5. An apparatus for treating ball-point pens comprising a casing having a circular chamber, a tube for holding a pen, said tube being rotated within said chamber and being open at one end and closed at its other end, means
25 for removably closing the last-mentioned end, a motor shaft attached to the tube at right angles to the longitudi-
30 nal axis of the tube, the casing having a pair of openings, one of the openings being an inlet opening through which a pen is inserted to reach the tube when the tube has its open end aligned with said opening, the second end being an outlet opening through which the pen is ejected after having been centrifuged by rotative move-
35 ment of the tube, and guard means rotatively carried by the tube for blocking off both of the openings except when the open end of the tube is in alignment therewith.

6. An apparatus for treating ball point pens comprising a motor, a switch for controlling current to the motor, the motor having a shaft, a tube mounted on said shaft transversely of the same, one end of the tube being closed and the opposite end being open and through which open end a ball-point pen is inserted to cause it to come to rest with its pointed end against the closed end of the tube, a casing enclosing the motor and tube, said casing having an entrance opening through which a pen is passed to reach the interior of the tube, and guard means for blocking off the opening except when the open end of the tube is aligned therewith.

7. In an apparatus for treating ball-point pens, as pro-
55 vided for in the claim 6, wherein the guard means is in the form of an annular rim carried by the tube, the casing having a circular chamber within it and in which the tube and its attached rim are rotated, said chamber having a wall extending around the rim, said wall having an outlet opening through which a pen is ejected when the tube is halted with the open end of the same in registry with said outlet opening.

8. In an apparatus for treating ball-point pens, a tube in which the pen, containing an ink-holding cartridge, is carried, said tube being mounted for rotation about a horizontal axis and having a fixed portion against which the ball-point of the pen is in contact, a horizontally arranged shaft connected to a motor for rotating the tube in a manner to centrifuge the ink in the cartridge and cause it to be forced toward the ball-point, said centrifugal action being also effective for forcing the ball-point of the pen against its support and thereby slightly displace the ball and permit the centrifuged ink to reach and coat the ball.
